(57) **CLAIM**

The ornamental design for a portion of a scanner, as shown and described.

DESCRIPTION

FIG. 1 is a front perspective view of a portion of a scanner showing our new design;

FIG. 2 is a front view thereof;

FIG. 3 is a rear view thereof;

FIG. 4 is a right side view thereof;

FIG. 5 is a top plan view thereof;

FIG. 6 is a bottom plan view thereof;

FIG. 7 is a front perspective view of the scanner with the top cover open;

FIG. 8 is a front perspective view of the scanner with the top cover and lower catch tray open; and,

FIG. 9 is a perspective view of the scanner with both top cover and lower catch tray shown in fullest extension.

The portions depicted in broken line are not claimed.

The dash-dot-dash lines represent the boundary between the claimed design and disclaimed portions, which also forms no part of claim.
